CLAIM

The ornamental design for a power distribution unit for shipyard fabrication, as shown and described.

DESCRIPTION

FIG. 1 is a top, front, right side perspective view of a power distribution unit for shipyard fabrication;

FIG. 2 is a front view thereof;

FIG. 3 is a rear view thereof;

FIG. 4 is a left side view thereof;

FIG. 5 is a right side view thereof;

FIG. 6 is a top plan thereof; and,

FIG. 7 is a bottom plan thereof.

The broken lines in the drawing depict portions of the power distribution unit for shipyard fabrication that form no part of the claimed design.
